CURTAIN FIXTURE

Ida Lundstrom, St. Louis, Mo.

Application March 11, 1943, Serial No. 478,812

15 Claims.

(Cl. 160—339)

This invention relates to curtain fixtures and the like.

The primary object of the invention is to provide a curtain fixture which will allow a curtain-rod to be raised and lowered with respect to stationary brackets, by means of a pull-cord, and which curtain fixture will be fully concealed behind the upper end of a curtain hung therefrom when the fixture is in its assembled operative position.

Another object of the invention is to provide a curtain fixture and the like, including stationary supporting brackets, carriers, a curtain-rod detachably secured to the carriers and a pull-cord secured at its ends to the carriers, whereby the carriers and curtain hanging rod assembled can be raised and lowered with respect to the stationary supporting brackets.

A further object of the invention is to provide a curtain fixture wherein the supporting brackets which include carrier guide members, will permit the curtain-rod carriers to be raised, in unison, from the brackets to a point above the guide members by pull on the pull-cord, then by release of pull on the cord lowered in a path in front of the carrier guide members to a desired lowered elevation within the reach of a person standing on the floor so that a curtain can be easily and readily hung on the curtain-rod, or removed therefrom, and thereafter raising the carriers and curtain-rod carried thereby to a predetermined elevation whereby the carriers will, upon release of pull on the cord, be supported by the stationary brackets in assembled relation.

A further object of the invention is to provide a pair of stationary brackets each including curtain-rod carrier supports, carrier guide members, carrier stops, and an eyelet through which the pull-cord passes.

A further object of the invention is to provide a pair of like curtain rod carriers adapted to be detachably supported by stationary brackets and to which the ends of a pull-cord is connected for raising and lowering the curtain-rod carriers with relation to curtain-rod carrier supporting brackets.

A still further object of the invention is to provide a fixture of the class described which is simple in construction, durable, easily operated, relatively neat in appearance, comparatively inexpensive in the cost of manufacture, and which can be made from sheet metal or plastics.

A still further object of my invention is to provide a bracket and curtain-rod and carriers

therefor, wherein the curtain-rod and the carriers therefor are separable.

A still further object of the invention is to provide a curtain-rod wherein the aforesaid carriers are formed integral with the ends of the curtain-rod.

With the above and other objects such, for instance, as convenience, safety and the like in view, the invention consists in the novel features 10 of construction of the individual parts of the fixture and arrangement and combination of parts hereinafter more fully described and finally pointed out in the claims hereto appended.

Referring to the drawings forming a part of 15 this specification, in which like characters of reference denote similar parts throughout the several views:

Fig. 1 is a front elevation of the invention showing a pair of curtains lowered to a position below 20 their normal hanging position so that they can be easily removed from one type of curtain-rod, or a clean pair placed on the curtain-rod.

Fig. 2 is a top plan view, with sections removed, 25 of the fixture in substantially full scale.

Fig. 3 is a top plan view of one end of the fixture showing a different type of curtain-rod connection with the carrier therefor.

Fig. 4 is a front elevation of one of the rod 30 carriers supporting brackets.

Fig. 5 is a vertical sectional view of the supporting bracket.

Fig. 6 is a front elevation of one end of the fixture showing the curtain-rod carrier supported by one of the brackets.

Fig. 7 is a side elevation of one of the brackets, partly broken away and partly in cross-section, a carrier supported thereby, a curtain-rod in cross-section, and a curtain hanging from the rod and showing the upper end of the curtain concealing 35 the fixture.

Fig. 8 is a top plan view of one of the curtain-rod carriers showing a detachable curtain hanging rod in dotted lines.

Fig. 9 is a front elevation of one end of the fixture and showing the curtain-rod and its carrier as lowered to a point below its normal curtain hanging position as when supported by the bracket.

Fig. 10 is a view of the fixture, in side elevation, and cross-section, and showing the curtain-rod and one of its carriers in full lines in a position when being lowered in front of the bracket guides, in dotted lines in an elevated position just prior to being lowered, and in dotted lines 50 in lowered position below the full line position.

Fig. 11 is a top plan view of a curtain-rod member and its end carrier as integral parts, and the rod being shown with a part thereof removed.

Fig. 12 is a front elevation of the rod and carrier shown in Fig. 13, and with a part of the rod broken away.

Fig. 13 is a side elevation of the rod and carrier shown in Figs. 11 and 12.

In carrying out my present invention, I employ, briefly, a pair of like stationary supporting brackets designated, generally as A, a pair of like curtain-rod carriers designated, generally as B, a suitable curtain-rod designated, generally as C, and a pull-cord designated, generally as D.

It will be here understood that the carriers B and the rod C supported thereby constitute, in their assembled relation, a curtain, or drape hanger which can be raised and lowered, as a unit, with relation to the stationary supporting brackets A. It will be further apparent that the carriers B are capable of supporting any of the present known types of curtain-rods.

More specifically, and with reference to the drawings, I have illustrated one embodiment of a stationary supporting bracket A which consists of a back-plate 1, a pair of spaced curtain-rod carrier guide members designated 2, a pair of spaced carrier supporting members 3 on the back-plate 1, a stop 4 on each guide member 2, and an eyelet supporting ear 5 at the upper end of each back-plate 1. As illustrated, each guide member 2 is integral with the back-plate 1 and is connected with opposite side edges thereof by means of the reduced side wall connections 6.

The guide members 2 are arranged in advance of the back-plate 1 and in spaced relation thereto, as well as in spaced relation to each other so as to provide a suitable gap 2' therebetween.

The lower end portions designated 7 of each guide member 2 is downwardly and forwardly inclined, and the upper end 8 of each guide member 2 is upwardly and rearwardly inclined, as shown in Figs. 4 and 5. The upper end faces 9 of the upper ends 8 of the guide members 2 are spaced a predetermined distance from the front face of the back-plate 1, or, in other words, terminate short of contact with the front face of the back-plate 1 to provide a space, or gap 10 therebetween for the passage of curtain-rod carrier cross-head hereinafter more fully described. The inner side edges of the lower ends 7 of the carrier guide members 2 are beveled, as at 7' so as to converge toward each other at the upper ends thereof.

The spaced carrier supporting members 3 on the back-plate 1 are shown, in one embodiment thereof, as shaped from the back-plate 1 and as having their upper faces 11 inclined forwardly and upwardly from the back-plate 1, and, if desired, the portions of these inclined upper faces 11 adjacent the front face of the back-plate 1 can be recessed, as at 12. Preferably, although not necessarily, the stop designated 4 on each guide member 2 is formed integral with the inner side edge of the upper inclined portions 8 of the carrier guide member 2. The stops 4 are disposed at a higher elevation than the upper faces 11 of the spaced carrier supports 3. The eyelet supporting ear 5 at the upper end of each back-plate 1 is bent forwardly to lie in a horizontal position and is provided with a suitable opening to receive a suitable eyelet 13 through which the pull-cord D can ride, as will be apparent from Figs. 1 and 2 of the drawings. The

back-plate 1 is provided with fastener receiving openings A' so that the brackets A can be secured to a window or other casing E by means of suitable fastening devices 1'.

More specifically, and with reference to the drawings, I have illustrated each curtain-rod carrier B, in one embodiment thereof, as comprising a channeled body member including the back wall 14 and the inner and outer side walls 15 and 16, respectively. The upper end of the back wall 14 terminates in a suitable cross-arm, head, or equivalent member 17 projecting beyond either side wall from the back wall 14. The inner side wall 15 at the upper end portion thereof is provided with an enlargement, or ear 18 projecting forwardly therefrom and is provided with a plurality of suitable vertically aligned openings 18' so that the two carriers can be attached to opposite ends of the pull-cord D. The outer side wall 16 of each carrier B is provided with a lateral projection, or wing 20 of suitable size and shape to accommodate the attachment thereto of any of the well known types of supports or curtain-rod brackets designated, generally as 22.

The pull-cord D, as illustrated in Fig. 1, is attached at one end, for instance the left end, to one of the curtain-rod carriers B, and at its opposite end to the other or right hand curtain-rod carrier B. The left hand end of the pull-cord D passes upwardly through the eyelet 13 on the left bracket A and across to the eyelet 13 of the right hand bracket A, and downwardly through the eyelet as shown in Fig. 2. The right end of the pull-cord passes upwardly over the eyelet 13 and then downwardly therethrough forming the pull-cord loop D' which is grasped by the operator when raising and lowering the curtain-rod C therewith. The free ends of the pull-cord D can be secured to the ears as through any of the openings 18' at different points desired, or necessary, to the proper functioning of the carriers. This pull-cord connection with the ears 18 causes the carriers to tilt after being raised to a point that the cross-heads 17 of the carriers B pass above the upper free ends of the ends 8 of the carrier guides 2 so that they cannot be lowered in the same path that the carriers B are raised. This arrangement causes the carrier heads 17 to ride downwardly on the outer or front faces of the carrier guides 2, as shown in dotted and full lines in Fig. 10 and causes the carriers to be raised with the cross-heads 17 moving upwardly behind the carrier guides 2 until they strike the stops 4, which upon release of pull on the cord allows the carrier heads 17 to drop to and rest upon the carrier supports 3.

It is believed to be well understood that curtain and drape rods are of many styles such, for instance, as tubular, solid and flat, and, it is also believed clearly apparent that these various conventional forms of curtain and drape hanging rods are supported by conventional forms of brackets which are secured directly to a window frame, a door and the like, and as far as applicant can learn have not been attached, or secured to curtain-rod carriers which can be pull-cord raised and lowered relative to a stationary supporting bracket secured to a window frame, door frame and the like.

The many advantages of the herein described invention will readily suggest themselves to those skilled in the art to which it appertains.

What I claim is:

1. In combination, a bracket having an eyelet adapted to be secured to a window frame or

the like, a carrier, a curtain-rod supported by the carrier, a cross-head on the carrier, means on the bracket for supporting the carrier in assembled relation with the bracket, and a pull-cord attached to the carrier and passing through the bracket eyelet for raising and lowering the carrier with relation to the bracket.

2. In combination, a bracket having an eyelet adapted to be secured to a window frame or the like, said bracket including a pair of supporting members, a pair of carrier guide members, stops respectively on the guide members, and an ear provided with an eyelet, a carrier, a cross-head at the upper end of the carrier adapted to normally rest on said supporting members, a curtain-rod, means for securing the curtain-rod to the carrier, and a pull-cord attached to the carrier and passing through said eyelet for raising and lowering the carrier and curtain-rod as a unit with relation to the bracket.

3. A device as defined in claim 2, wherein the carrier guide members are spaced from the back of the bracket and spaced from each other, the guide members having their lower ends inclined downwardly and forwardly and the inner side edges diverging downwardly, the upper end of the guide members being inclined upwardly and rearwardly but terminating short of the back of the bracket to provide a gap for passage upwardly of the carrier cross-head when raising the carrier from the aforesaid supporting members.

4. In a fixture of the class described, a bracket including a carrier rest, carrier guide members each having upper and lower end portions inclined in the same general direction, a carrier stop on each guide member, a carrier, a cross-head at its upper end, a wing on the carrier, and a curtain hanging rod supported by the carrier wing.

5. In a fixture of the class described, a stationary supporting bracket including a carrier rest, carrier guide members each having upper and lower end portions inclined in the same general direction, a carrier stop on each guide member, a curtain hanging rod, means including a cross-head for supporting the rod at an end thereof, means for raising and lowering said means together with the rod, and causing the cross-head to move upwardly behind the guide members to normal hanging position from the bracket, and said first means being further raisable to elevate the cross-head to a point beyond the upper ends of the guide members, whereupon said cross-head swings to a position to the front of the upper end of the guides, thereby positioning said first means for descent in front of said guides.

6. In a curtain fixture, a curtain-rod, a curtain-rod carrier, a cross-head at the upper end of the carrier, a bracket for supporting said carrier in normal curtain hanging position, said bracket including carrier guide members integral with and spaced from the back of the bracket, said guide members having inclined upper and lower ends with the lower edges thereof diverging downwardly, means slidably supported by the bracket from which the carrier is suspended for raising the carrier in a path behind the guide members for support on the bracket and upwardly behind the guide members from its supported position to a point above the upper ends of the guide members, whereupon said cross-head swings to a position to the front of the upper end of the guides, thereby positioning

said cross-head for descent in front of said guides.

7. A curtain-rod supporting bracket comprising a back plate, a pair of curtain-rod carrier supports on said bracket, a pair of curtain-rod carrier guide members spaced from the back plate and spaced from each other, means for connecting the guide members with the back plate, a stop on each guide member disposed in spaced relation above said curtain-rod carrier supports and an apertured pull-cord guide member projecting forwardly from the upper end of the back plate.

8. A curtain-rod supporting bracket comprising a back plate, means on the back plate for supporting a curtain-rod carrier, a pair of curtain-rod carrier guide members spaced from and connected with the back plate and spaced from each other, a curtain-rod carrier stop on each carrier guide member, the upper and lower ends of the guide members being inclined in the same general direction, the lower inclined ends of the guide members having their inner edges inclined, and a pull-cord guide member projecting forwardly from the upper end of the back plate and centered midway between the side edges of the bracket.

9. A curtain-rod carrier comprising a longitudinally channeled member, a cross-head at the upper end of the back of the channeled member, an enlargement projecting forwardly from the upper end portion of the inner side wall of the channeled member for connection with a pull-cord, and a curtain-rod supporting plate projecting laterally from the upper end portion of the outer side wall of the channeled member.

10. In a fixture of the class described having, in combination, a bracket, a curtain-rod, a carrier on the curtain-rod, a head on the carrier, guide means on the bracket for directing the carrier head in an upward path of travel behind said guide means and for directing the carrier head in the downward path of travel in front of said guide means.

11. In a fixture as defined in claim 10, including inwardly projecting means on the guide means to serve as a stop for the carrier head, and means on the bracket for supporting the carrier head below and to the rear of the carrier stops.

12. In combination, a bracket including means to support a carrier, carrier guide means mounted on and spaced from the back of the bracket, a carrier, a cross-head on the carrier, a pull cord slidable over said bracket from a point above and to the front of the upper end of said guide means for raising the carrier with the cross-head thereof moving upwardly behind the guide members to cause the cross-head to rest on the carrier supports and for elevating the cross-head behind the guide members to a position beyond the upper end of the guide members whereupon said cross-head swings to a position to the front of the upper end of the carrier guide means, thereby positioning the cross-head for descent in front of the carrier guide means.

13. In a curtain fixture, a bracket, a carrier adapted to carry a curtain rod, said bracket including a carrier guide integral with and spaced from the back of the bracket, carrier supporting means on the back of the bracket, and means on the carrier guide to stop raising movement of the carrier at a predetermined elevation, means on the carrier adapted to rest on the said carrier supporting means, a pull cord guided by the bracket from a point above and to the front of the upper end of said guide and to which the

carrier is connected for raising the carrier in a vertical path to bring the said means on the carrier to rest on the carrier support and to raise said means on the carrier from said supporting means to a position above the carrier guide, whereupon said means on the carrier swings to a position to the front of the upper end of the carrier guide, thereby positioning said means on the carrier for descent in front of the said carrier guide.

14. A curtain-rod carrier including a member having a cross-head at one end thereof, a forwardly projecting ear below the cross-head adapted to be connected to a pull cord, and a curtain-rod forming a part of said member.

15. In a curtain fixture, a bracket, a curtain-rod and a carrier for the curtain-rod, said carrier including a cross-head and an ear below and projecting to the front of the cross-head, said

bracket having an eyelet at the upper end thereof and including a carrier cross-head support and a cross-head guide, said guide extending generally downwardly below said eyelet and spaced from and in front of the cross-head support and connected to a side edge of the bracket, the upper end of said guide being to the rear of said eyelet and the lower end of said guide being spaced forwardly of said eyelet, a pull cord connected to the ear of the carrier and passing through said eyelet whereby the cross-head may be raised behind the guide to a position of rest upon the aforesaid support and raised from the support of a position above the upper end of the guide and then lowered in front of and in sliding contact with the guide to a predetermined position below the bracket.

IDA LUNDSTROM.
